Certificate

Patent No. D 435,254

Patented: December 19, 2000

On petition requesting issuance of a certificate for correction of inventorship pursuant to 35 U.S.C. 256, it has been found that the above-identified patent, through error and without deceptive intent, improperly sets forth the inventorship.

Accordingly, it is hereby certified that the correct inventorship of this patent is: Arthur L. Gaudette, Richard J. Takahashi, Christopher D. Lucero and Rico L. Zorkendorfer.

Signed and Sealed this First Day of May, 2001.
